UNITED STATES PATENT OFFICE.

CHARLES W. HARMAN, OF NEW ROCHELLE, NEW YORK.

DESIGN FOR A HANDLE FOR SPOONS, FORKS, OR SIMILAR ARTICLES.

45,300.

Specification for Design.

Patented Feb. 24, 1914.

Application filed December 31, 1913. Serial No. 809,756. Term of patent 7 years.

To all whom it may concern:

Be it known that I, CHARLES W. HARMAN, a citizen of the United States, and a resident of New Rochelle, in the county of Westchester and State of New York, have invented a certain new, original, and ornamental Design for a Handle for a Spoon, Fork, or Similar Article, of which the following is a specification.

In the accompanying drawing, Figure 1 is a view in elevation of a spoon showing my

new design applied thereto; and Fig. 2 a sectional view taken on the line 2—2 of Fig. 1, the tines of a fork being shown in dotted lines in Fig. 1.

I claim:

The ornamental design for a handle for a spoon, fork or similar article, as shown.

CHARLES W. HARMAN.
